CHARLES H. DOUGLAS, OF HARTFORD, CONNECTICUT.

Letters Patent No. 84,865, dated December 15, 1868.

GAME OF COLORS.

The Schedule referred to in these Letters Patent and making part of the same.

To all whom it may concern:

Be it known that I, CHARLES H. DOUGLAS, of Hartford, in the county of Hartford, and State of Connecticut, have invented a new and useful game for children, which I call "The Game of Colors;" and I do hereby declare that the following is a full and exact description of the same, reference being had to the accompanying drawings, making a part of this specification.

A is a board, of thick paper, pasteboard, or any suitable material, on which are printed or painted six different colors, viz, red, blue, yellow, purple, pink, and green, with their names placed thereon.

B are six different-colored tops, corresponding with the six colors on the board.

C is an embossed ring, to prevent the said tops from running off when spun.

One player at a time spins all the tops on this board, with the thumb and finger, and, when they cease spinning, the game is counted from the positions the points of these tops may chance to occupy thereon, as follows:

If the point of any top rests upon the white centre, it counts the player four, as that harmonizes with any and all the colors; if upon its own color, that is a match, and counts three; if upon a harmonious contrast, that is a harmony, and counts two; and if upon any other color, it counts but one.

The players spin alternately, and the one who first obtains ten counts, wins the game.

In the accompanying drawing, the tops are represented at rest, after having been spun, and count the player as follows:

Green rests upon green—a match.....	3
Pink upon purple—a harmony.....	2
Yellow upon red—not a harmony.....	1

Result of this spin..... 6

The harmonious contrasts are given on the card of directions which accompanies this game, as follows:

Blue contrasts with yellow.

Yellow contrasts with blue, purple, and green.

Purple contrasts with yellow, green, and pink.

Pink contrasts with green and purple.

Green contrasts with red, pink, purple, and yellow.

Red contrasts with green.

The prime object of this game is to familiarize children and youth with the names and harmonies of colors, and to give refinement and cultivation to the sense of color, while it is affording them a fine amusement.

It may consist of any desired number or variety of colors or tops. Balls or dice of various colors may be used, instead of tops, but the effect is not as pretty or amusing.

Dice, with different-colored sides, may be matched with each other or upon a color, by chance throws, with similar results.

I claim the game herein specified, as a new article of manufacture.

CHAS. H. DOUGLAS.
